*Primary Examiner—Philip S. Hyder***[57] CLAIM**

The ornamental design for a hand held skate sharpener, as shown and described.

DESCRIPTION

FIG. 1 is a perspective view of a hand held skate sharpener, showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a top, front and right side perspective view thereof, wherein the broken line showings of the skate and hands are for illustrative purposes only and form no part of the claimed design;

FIG. 9 is a top, front and left side perspective view thereof, wherein the broken line showings of the skate and hands are for illustrative purposes only and form no part of the claimed design; and,

FIG. 10 is a front elevational view thereof, wherein the broken line showings of the skate and table top are for illustrative purposes only and form no part of the claimed design.
